SEWING MACHINE

Filed June 15, 1921

UNITED STATES PATENT OFFICE.

AUGUSTINE F. LITTLEFIELD, OF LYNN, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed June 15, 1921. Serial No. 477,817.

The present invention relates to sewing machines and more particularly to wax thread chain stitch inseam shoe sewing machines.

5 In the practical operation of sewing machines of this type, the operator in manipulating the shoe to disengage it from the machine, pulls a certain amount of thread from the supply through the stripper of the 10 thread waxing device. In order that the thread tensioning devices of the machine may not interfere with such drawing of thread from the supply, means are usually provided for releasing the thread tensioning 15 devices on stopping the machine. The thread stripper, however, offers considerable resistance to the travel of the thread and it has been found that the stripper cannot be tightened beyond a certain limit without 20 causing it to furnish so much resistance to the travel of the thread that the seam will be unravelled when it is attempted to draw the thread through the stripper during the removal of the shoe from the machine. With the stripper set as tight as is 25 practicable and still permit such drawing of the thread from the supply, a great deal more wax than is necessary for satisfactory sewing is left on the thread after it passes 30 through the stripper, and thus a large percentage of the wax is wasted. It has also been found that in the removal of the shoe a great deal more thread than is necessary is 35 often drawn from the supply.

The principal object of the present invention is to provide means for overcoming the disadvantages above described.

With this and other objects in view a feature of the present invention contemplates 40 the provision in a sewing machine of means for drawing a predetermined amount of thread from the supply to furnish slack thread for the removal of the work after the sewing operation. The amount of thread 45 thus drawn from the supply preferably is only sufficient to permit the work to be removed in the usual manner so that there is no danger of thread being wasted during the removal of the work. In the preferred 50 embodiment of the invention the means for drawing thread from the supply operates independently of the movement of the work during its removal, so that with the use of this feature in a wax thread sewing machine

having a thread stripper, the drawing of the thread from the supply may be accomplished irrespective of the tightness of the stripper without danger of unravelling the seam.

Other features of the invention consist in 60 certain constructions, arrangements and combinations of parts hereinafter described and claimed, the advantages of which will be obvious to those skilled in the art.

The several features of the invention will 65 be clearly understood from the following description and accompanying drawings in which:

Figure 1 is a side elevation partly in section of the head of a wax thread chain stitch 70 inseam shoe sewing machine embodying the features in their preferred form; Fig. 2 is a detail sectional view taken on the line 2-2 of Fig. 1.

The machine illustrated in the drawings 75 has the same general construction and mode of operation as the machine illustrated and described in the patent to Seely No. 1,240,094, dated September 11, 1917. This machine is provided with a curved hook needle 80 2, a thread arm 4, a looper 6, a thread gripping and cutting device 8, a welt guide 10, a back rest or bunter 12, and a thread tension wheel 14. The thread gripping and cutting device 8 is mounted on the looper and is 85 conveniently arranged to enable the thread extending between the stitch forming devices and the work to be inserted in the device and cut during the removal of the work. The thread tension wheel is secured 90 to one end of a shaft 16 which extends 95 through and is journaled in a pair of spaced bearings 18 formed on a bracket on the machine frame. In order to restrain the rotation of the shaft 16 to cause the tension 100 wheel to exert the required amount of tension on the thread during the sewing operation, a brake drum 20 is secured to the shaft 16 between the bearings 18, the periphery of which is engaged by a spring-pressed brake shoe 22. The brake shoe 22 is pivotally mounted on a lever 24 midway of its ends, which lever is pivotally mounted at its forward end on the machine frame and is urged downwardly by a coiled spring 105 26 connected with its rear end. The machine is also provided with a driving shaft 28 which during the normal operation of the

machine is driven in a counter clockwise direction, viewing Fig. 1. Upon stopping the machine either manually, as described in the patent to Seely above referred to, or 5 automatically by means of a stopping mechanism such as is described in the patent to Topham, No. 1,099,326, dated June 9, 1914, the rotation of the driving shaft is reversed to drive the machine in a reverse direction 10 to a position in which the needle is clear of the work and free from the thread.

During the normal operation of the machine a curved portion 30 of a swinging arm 32 engages a collar 34 carried by the shaft, 15 but upon the reversal of the rotation of the driving shaft the arm 32 is shifted rearwardly and its forward end is swung upwardly to bring a curved portion 36 thereof into engagement with the collar 34. Upon again 20 starting the machine the swinging arm 32 is moved to return the curved portion 30 thereof into engagement with the collar 34. The rear end of the swinging arm 32 is pivotally mounted on the upper end of a lever 25 38 pivoted at 40 on the machine frame, which lever upon reversal of the rotation of the driving shaft is actuated by the swinging arm 32 to retract the welt guide through suitable connections. The parts above described 30 are the same as the corresponding parts of the machine illustrated and described in the patent to Seely hereinbefore referred to, to which reference may be had for a complete description of this and other 35 parts of the machine not fully described herein.

In the machine illustrated in the drawings mechanism is provided for drawing a pre-determined amount of thread from the supply 40 upon stopping the machine, which amount of thread is sufficient to meet the requirements in the removal of the work. As shown, this mechanism comprises the tension wheel 14 and suitable connections 45 through which it is rotated a predetermined number of degrees by the swinging arm 32 upon stopping the machine. The connection between the tension wheel and the arm 32 comprises a grooved wheel or pulley 42 loosely mounted on one end of the tension 50 wheel shaft 16. A pair of diametrically opposed spring pressed pawls 44 are mounted on the outer face of the pulley 42 which engage a ratchet wheel 46 secured to the tension wheel shaft. The grooved periphery of the pulley 42 is engaged by a chain or strap 47 having one end connected with a coiled spring 48 secured to the frame and its other end connected with the lower end of a rearwardly extending depending arm 50 which is integral with the swinging arm 32. With this construction it will be apparent that when the forward end of the arm 32 is 60 swung upwardly to position the curved portion 36 thereof in engagement with the col-

lar 34 on the driving shaft upon the reversal in the direction of rotation of the shaft, the depending arm 50 will act through the strap 47 to rotate the pulley 42 a predetermined number of degrees in a clockwise direction. During such rotation of the pulley 42 the ratchet and pawl connection between the pulley and the tension wheel shaft 16 will cause the tension wheel to be rotated with the pulley to draw thread from the supply. When the swinging arm 32 is 70 swung downwardly to position the curved portion 30 thereof in engagement with the collar 34 of the driving shaft upon starting the machine into operation, the coiled spring 80 48 will be permitted to act through the strap 47 to return the pulley 42 to its normal angular position. The ratchet and pawl connection between the pulley 42 and the shaft 16 permits such return movement of the pulley 85 42 independently of the tension wheel and shaft, and also permits the operation of the tension wheel in the usual manner during the normal operation of the machine independently of the pulley 42 so that the mechanism does not interfere with the operation of the tension wheel during the sewing operation.

It will be apparent from the foregoing 90 that the required amount of thread is drawn from the supply for the removal of the work without placing any strain on the stretch of thread extending from the thread tensioning devices to the work, so that irrespective of the tightness of the thread stripping device there is no danger of the seam being unravelled during the removal of the work. It will also be apparent that a mechanism for releasing the thread tension device on stopping the machine, as is customary in machines of this type, is unnecessary and the brake shoe 22 of the tension device 95 may act uniformly at all times on the tension wheel.

While the features described above are 100 well adapted for use in a wax thread chain stitch inseam shoe sewing machine, it is to be understood that, except as defined in the claims, certain features of the invention are 105 not limited to use in a sewing machine of this type.

The several features of the invention having been indicated and a machine embodying the features in their preferred form having been specifically described, what is claimed 110 is:—

1. A sewing machine having, in combination, stitch forming devices, a tension wheel over which the thread passes, and means 115 for rotating the tension wheel a predetermined number of degrees upon stopping the machine acting at the same time to relieve the strain on the thread between the tension wheel and the work and to furnish slack thread for the removal of the work. 120

2. A sewing machine having, in combination, stitch forming devices, a shaft, a tension wheel carried by the shaft over which the thread passes, a disk loosely mounted on the shaft, means for rotating the disk a predetermined number of degrees upon stopping the machine, and a ratchet and pawl connection between the disk and shaft to cause rotation of the tension wheel to draw thread from the supply upon stopping the machine and to permit rotation of the tension wheel independently of the disk upon a strain being placed on the thread.
3. A sewing machine having, in combination, stitch forming devices, a driving shaft for the machine driven in one direction during the sewing operation and in the reverse direction upon stopping the machine, and means actuated by the shaft upon rotation thereof in said reverse direction for drawing thread from the supply to furnish slack thread for the removal of the work.
4. A sewing machine having, in combination, stitch forming devices, a driving shaft for the machine driven in one direction during the sewing operation and in the reverse direction upon stopping the machine, thread tensioning devices, and connections between the threaded tensioning devices and the shaft for actuating said devices upon rotation of the shaft in said reverse direction for drawing thread from the supply to furnish slack thread for the removal of the work.
5. A sewing machine having, in combination, stitch forming devices, a driving shaft for the machine driven in one direction during the sewing operation and in the reverse direction upon stopping the machine, a thread tension wheel, and connections between the tension wheel and the driving shaft for rotating the tension wheel upon rotation of the shaft in said reverse direction for drawing thread from the supply to furnish slack thread for the removal of the work.
6. A sewing machine having, in combination, stitch forming devices, a shaft, a tension wheel carried by the shaft, a pulley loosely mounted on the shaft, a ratchet and pawl connection between the pulley and the shaft to cause rotation of the tension wheel to draw thread from the supply upon rotation of the pulley in one direction and to permit rotation of the tension wheel independently of the pulley upon a strain being placed on the thread, means for rotating the pulley in the direction to rotate the tension wheel comprising a strap in frictional engagement with the peripheral surface of the pulley, a spring connected with one end of the strap, a lever connected with the other end of the strap, and means for rocking the lever to rotate the pulley in said direction against the tension of said spring.
7. A sewing machine having in combination, stitch forming devices, a tension wheel, means for rotating the tension wheel a predetermined number of degrees upon stopping the machine acting at the same time to relieve the strain on the thread between the tension wheel and the work and to furnish slack thread from the supply for the removal of the work, and a brake for restraining the rotation of the tension wheel to exert a uniform force on the wheel during the sewing and work removing operations.
8. A sewing machine having, in combination, stitch forming devices, a thread tension wheel, and means for rotating the tension wheel a predetermined number of degrees after the sewing operation to draw thread from the supply while relieving the strain on the thread between the tension wheel and the work.
9. A sewing machine having, in combination, stitch forming devices, a tension wheel over which the thread passes, a cam shaft, and a train of mechanism actuated from the cam shaft and forming a permanent part of the machine for rotating the tension wheel a predetermined number of degrees upon stopping the machine to furnish slack thread for the removal of the work.
